UNITED STATES PATENT OFFICE.

ARTHUR L. MORGAN, OF MONTREAL, QUEBEC, CANADA.

CHAIN GRATE FOR FURNACES.

Application filed September 25, 1925. Serial No. 58,659.

This invention relates to new and useful improvements in chain stoker grates for furnaces and particularly to the means for locking the links forming the fuel support to the grate link rods, which extend across the full width of the grate and the object of the invention is to provide a very efficient and simple link grate of the class described, in which any one link will be easily removed 10 without disturbing or dismantling any of the adjacent links, thereby facilitating repairs to such grates should said links become burnt out or broken through excessive wear, accident or the like.

15 Another object is to provide a chain stoker grate which will be very inexpensive to manufacture and easy to assemble in place.

In my invention, I provide a chain stoker grate of the endless type built of a plurality 20 of links, mounted on rods which extend across the full width or approximately the full width of the furnace. The links forming the chain are provided with fuel supporting surfaces and are mounted on the 25 rods, open slots being provided in the depending webs, to form the bearing or contacting surfaces for the rods. The slots are provided with flaring ends to facilitate the 30 assembling of the grate and to hold the links in place. Key pins are driven through holes 35 formed in the links, the lower ends of said holes being so formed that the lowermost ends of the key pins are bent or curved around the lowermost surface of the link rods, to hold the links in position.

In the drawings which show one embodiment of my invention;

Figure 1 is a side elevation of the links showing the key pins.

40 Figure 2 is an end elevation of the link shown in Figure 1.

Figure 3 is an end elevation of a side link, the side elevation of which is similar to Figure 1.

45 Figure 4 is a plan of the link shown in Figure 1.

Figure 5 is a plan view of a portion of a chain stoker grate constructed according to my invention.

50 Referring more particularly to the drawings, 11 designates a stoker grate, formed of a series of intermediate links 12 and side links 13, mounted on rods 14 extending across the grate. In the drawings, I have 55 shown them in staggered relationship but

this may be altered to suit the requirements of the owner of the furnace. The links have flat upper surfaces 15, which form a supporting means for the fuel as it passes through the furnace. The surfaces are 60 formed integral with the vertically disposed webs 16, which have enlarged bosses 17, with slots formed therein which engage with and rest upon the rods 14. In the drawing the rods are shown round and the bearing surfaces of the slots semicircular, but these may be made oval or square to suit the shape of the rods used. Each slot is open at one end 65 18, and flares outwardly toward that end to allow for easy erection or dismantling of 70 the links. Vertically disposed holes 19, are formed in the webs of the links in close proximity to the slots and the lowermost ends 20 of said holes are curved towards the slots and communicate therewith to guide 75 key pins 21 driven into said holes, toward and under the rods 14 to lock the links in position. In the drawing the key pins are shown of square cross section for illustrative 80 purposes only and it will be readily understood that the section of the key pins may be modified without departing from the spirit of the invention. The bosses 17 extend beyond the edges of the fuel bearing 85 surfaces of the links and corrugations or grooves 22 may be formed in the surfaces to allow air to be blown into the fuel from the underside of the grate. In Figure 2 which shows one of the intermediate links, the web 16 is centrally disposed and in Figure 3, 90 which shows a side link the web 16^a is shown to one side of the centre line but this is only a manufacturer's detail and is shown as a modification.

In operation the key pins hold the links 95 in bearing engagement with the rods 14, and form a simple means for facilitating the erection of the grate. The links are dropped onto the rods 14 and the key pins are driven through the holes 19, the lower ends of 100 which are formed in such a manner as to cause the key pins to curve towards and partially around the rods 14, to hold the links in position. In dismantling the lower ends of the key pins may be broken off or 105 bent straight by means of a crow bar to clear the rods 14, so that the link may be easily removed. This construction is very simple and allows one link to be removed without disturbing the remainder of the links form- 110

ing the grate. By providing grooves in the sides of the fuel bearing surfaces, air from the lower parts of the furnace may be blown through the grate to assist materially in complete combustion of the gases arising from the burning of the fuel carried by the grate.

Having thus described my invention what I claim is:—

- 19 1. A chain grate link presenting a fuel bearing surface formed with an integral depending web having a pair of spaced slots extending upwardly from the lower edge thereof to receive suitable supporting rods, there being a pair of passages formed in said bearing surfaces and web to extend downwardly therethrough from the top of the bearing surface, said passages being located between said slots and having their lower ends curved toward the slots to communicate therewith near the mouth portions of the slots and key pins adapted to be driven downwardly through said passages whereby the lower ends of the pins are deflected by

the curved portions of the passages to project across the mouth portions of the slots to retain the supporting rods therein. 25

2. A chain grate link presenting a fuel bearing surface formed with an integral depending web having a slot extending inwardly from one edge thereof to receive a link supporting rod, there being a passage formed in said bearing surface and web to extend downwardly therethrough from the top of the bearing surface at one side of 35 the slot with the lower end of the passage curving toward the slot and communicating therewith at one side of and adjacent the mouth portion of the slot and a pin of greater length than said passage adapted to 40 be driven downwardly therethrough whereby the lower end of the pin is guided by the curved portion of the passage to project across the mouth of the slot to retain the supporting rod therein. 45

In witness whereof, I have hereunto set my hand.

ARTHUR L. MORGAN.
